Primary Examiner — Stella M Reid*Assistant Examiner* — Elizabeth J Oswecki(74) *Attorney, Agent, or Firm* — SAIDMAN DesignLaw Group(57) **CLAIM**

The ornamental design for a bottle, as shown and described.

DESCRIPTION

FIG. 1 is a front view of a bottle showing our new design, the rear view being a mirror image thereof;

FIG. 2 is a side view thereof;

FIG. 3 is a left side view thereof;

FIG. 4 is a right side view thereof;

FIG. 5 is a top view thereof; and,

FIG. 6 is a bottom view thereof.

The broken line showing of the pour spout and molding details is included for the purpose of illustration only and forms no part of the claimed design.
